MACHINE FOR POLISHING JOURNALS OF
RAILROAD VEHICLE AXLES

Walter William Dixon, Detroit, Mich., assignor to
The New York Central Railroad Company, a
corporation of New York

Application October 19, 1937, Serial No. 169,890

1 Claim. (Cl. 51—34)

My invention relates to means for polishing the journals of railroad vehicle axles.

As is well known, the axle and wheel assembly of railroad vehicles is stored in yards and is, therefore, exposed to the elements, as a result of which the assembly becomes coated with rust. Before the assembly may be safely used it is necessary to remove the rust and other deposit from the journal of the axle and it has been found a difficult and time consuming job to do this properly without changing radius or scoring. At the present time axle journals are either polished by hand when the wheels are not in a lathe for other work or by the combination of hand and machine work when axles or mounting wheels are in a lathe for other work.

The object of my invention is to provide a machine for polishing the journals of axles that will not only reduce the time and labor necessary to do this work, as it is now handled, but will do it with a higher degree of accuracy, and with this and other objects in view my invention consists of the parts and combination of parts as will be hereinafter pointed out, and more particularly pointed out in the appended claim.

In the drawings:

Figure 1 is a perspective view of my improved machine in position for assembly with an axle journal.

Figure 2 is a similar view of my improved machine in assembly with an axle journal.

Figure 3 is a side elevation of my machine.

Figure 4 is a top plan view of Figure 3.

Figure 5 is a side elevation of the polishing frame.

Figure 6 is a front elevation of Figure 5.

Figure 7 is a rear elevation of Figure 5.

Figure 8 is a front elevation of the elevator.

The reference numeral 1 designates the track rails suitably secured to a base 2. A carriage 3 is provided with wheels 4 and designed to reciprocate on said tracks, and is held firmly on the rails 1 at each side by means of a spring 5. An elevator frame work 6 is mounted on the carriage 3 and travels with the carriage, said elevator having an elevating screw 7 on which is mounted a cross head 8 which is adjusted up or down according to the direction in which the screw is revolved by the handle 9. The side walls of the elevator frame are provided with elongated slots 10 in which the ends of the bolt 11 are mounted. The cross head 8 is connected with the screw 7 by means of the threaded element 12. The cross head has a forwardly projection platform or support 13 on which is mounted a non-reversible air,

or other suitable motor 14, which is suitably connected by the shaft 15 to the polishing element.

The polishing element, or frame, comprises bars 16 which are connected at their rear ends to a frame 17 which has an opening 18 in which the shaft 15 of the motor 14 is secured. The upper and lower pairs of arms 16 are hinged as at 19, as shown in Figures 1 and 7, whereby they may be separated, as shown in Figure 1, to receive the axle journal between them. These pairs of arms are held in closed position by means of the locks 19' (see Figure 6). The forward ends of the arms 16 form a cage pocket in which are secured wooden, or other suitable, blocks or polishing heads 20, each lined with a pad of emery, or other suitable cloth 21 that is folded so that it overlaps the block approximately one-half inch toward the journal fillet, and about one-quarter inch toward the collar of the journal. The arms 16 are of sufficient length and are positioned relative to 20 each other at a sufficient diameter to permit the blocks 20 to travel the full length of the journals on the largest size axle.

A motor 22 of the reversible type is bolted to the end of the rails 1, and is directly connected to a feed screw 23, which screw is threaded through a lug 24 bolted to the underside of the carriage 3, so that when the motor 22 is in operation the rotation of the screw 23 forces the carriage 3 along the rails forward and backward as the motor is reversed.

An automatic trip for reversing the motor 22 is connected to the side of the rails and comprises two adjustable stops 24' mounted in standards 25, said standards being adjustably mounted on the rod 26 and held in adjusted position by means of the set screws 27. A tripper 28 is bolted to the carriage 3 and travels back and forth with the carriage and is so located that it comes in contact with one of the adjustable stops 24' when the carriage 3 has reached the predetermined end of travel. This is determined by the length of the journal. As the bar 26 is moved it operates the links 28' and 29, and the link 29 operates the lever 30 which is directly connected to the reversing valve on the motor 22. The link 28' is pivoted at 31 with its lower end connected to a spring 32.

When the journals of a mounted pair of wheels are ready to be polished the wheels are rolled into line with the center of the carriage 3 and the elevator 6; the arms 16 with the blocks 20 and polishing material 21 are separated, as shown in Figure 1. The arms 16 are now closed and locked together by means of the locks 19 with the polishing material bearing against the sur-

face of the journal, as shown in Figure 2. The motor 14, when operated, starts the blocks 20 revolving on the journal. The reversible motor 22 is then started and the adjustable stops 24 so set that the reversible motor 22 will be reversed when the blocks 20 have reached the ends of the journal, thus reversing the travel of the blocks 20 and polishing the journal from end to end.

Axes not mounted on wheels may also have 10 the journals polished with the use of this machine if they are properly mounted.

The emery block motion inward ends approximately at the base of the journal fillet, the overlapping emery cloth preceding through the fillet 15 curvature, giving a fine finish without changing radius or scoring; and in this manner on the reverse motion the small overlap of the emery cloth on the outside completes the polish of radius at the collar of the journal before the travel is completed. As the work is done automatically the 20 operator only applies oil on the journal a few times during the operation. The final operation is made with a carpet or felt pad which overlaps the blocks 21 in the same manner as the emery 25 cloth, thus giving the entire surface the high polish desired.

The springs 5 are secured at their lower ends to the frame 5', which in turn is connected with the axle 5a, on which are mounted the rollers 5b which run on the lower edge or face of the rails 1.

It is obvious that changes may be made in the 5 details of construction without departing from the spirit of the invention defined in the appended claim.

What I claim is:

In a device for polishing axle journals, a shaft, 10 a polishing frame comprising a frame member disposed at one end of the frame and fixed to the shaft, sets of arms hinged at one end to the frame member, semi-cylindrical polishing heads fixed to the free ends of the arms at the opposite end of 15 the frame and movable with the sets of arms toward and from each other to close and open said end of the frame and move the polishing heads toward or from each other, means for connecting like arms of the sets at the free end of 20 the same to hold the frame closed and the heads in operative relation, and means for rotating and reciprocating said polishing frame.

WALTER WILLIAM DIXON. 25
